P. GROEBER.

WALL PAPER.

No. 15,173.

Patented July 29, 1884.

UNITED STATES PATENT OFFICE.

PAUL GROEBER, OF NEW YORK, N. Y.

DESIGN FOR WALL-PAPER.

SPECIFICATION forming part of Design No. 15,173, dated July 29, 1884.

Application filed April 11, 1884. Term of patent 3½ years.

To all whom it may concern:

Be it known that I, PAUL GROEBER, a citizen of the United States, residing in the city of New York, county and State of New York, 5 have invented and produced a new and original Design for Wall or Ceiling Covering, which is especially intended as a dado, of which the following is a specification.

The drawing represents a front plan view 10 of the design.

The design is floral in its character and in the Japanese style. It consists of three molded bands, *a a a*, of equal width, each decorated with a floral rod, *b*, with leaves *c c* springing 15 from either side and two clusters of bloom-buds, *d d*. This part of the design is intersected at regular intervals by a square-molded

decoration, *e*, having for a center a radiating star-like rosette, *f*, which overlaps the surrounding molding. The edges of the rosettes 20 are escalloped, and the centers form a cluster of beads.

I claim—

The design for a wall and ceiling covering, consisting of the representation of bands, 25 floral rods with leaves and clusters of bloom-buds, and square-shaped ornamented figures, described in the foregoing specification and shown in the accompanying illustration.

PAUL GROEBER.
